UNITED STATES PATENT OFFICE.

ANDREW SAVAGE AND JOHN Y. SAVAGE, OF SCOTLAND NECK, N. C.

PLANTER.

SPECIFICATION forming part of Letters Patent No. 322,752, dated July 21, 1885.

Application filed September 15, 1884. (No model.)

To all whom it may concern:

Be it known that we, ANDREW SAVAGE and JOHN Y. SAVAGE, both residents of Scotland Neck, in the county of Halifax and State of North Carolina, have invented certain new and useful Improvements in Planters; and we do hereby declare that the following is a full, clear, and exact description of the invention, which will enable others skilled in the art to 10 which it appertains to make and use the same, reference being had to the accompanying drawings, which form a part of this specification, and in which—

Figure 1 is a side view of my improved combined seed and cotton planter. Fig. 2 is a longitudinal vertical sectional view of the same. Fig. 3 is a vertical transverse sectional view taken through the axle of the machine. Fig. 4 is a bottom plan, and Fig. 5 is a detail 20 view, on a larger scale, of the seeding wheel or disk.

The same letters refer to the same parts in all the figures.

This invention relates to seeders or planters 25 for corn, cotton, and other seed; and it has for its object to produce a device which shall possess superior advantages in point of simplicity, durability, and general efficiency.

With these ends in view it consists in the 30 improved construction and combination of parts which will be hereinafter fully described, and particularly pointed out in the claims.

In the drawings hereto annexed, A designates the frame of the machine, which is 35 mounted upon a revolving axle, B, having the transporting-wheels C C. The said axle is journaled in boxes D D upon the under side of the frame.

E designates the hopper, which is constructed 40 in two parts, the lower one of which, F, is inserted from the under side of the frame and provided with notches G G to accommodate the axle, the upper ends of the said notches being covered by plates H upon the inner 45 sides of the upper part of the hopper.

The front part of the frame carries the furrow-opener, the standard of which, I, is constructed of a single piece of metal bent into the shape shown in the drawings, and having 50 the upper end of its rear leg slit and bent in opposite directions, so as to form the flanges J J, by which it is connected to the frame.

To the said rear leg of the standard are pivoted the covering-blades K K, the rear ends of which are curved or twisted, as shown, so as to 55 drag the soil in a light ridge over the seed deposited by the planter.

The bottom L of the hopper is made preferably of sheet metal, and it has near its front end a V-shaped slot, M, which may be partially covered by a pivoted slide, N, so as to regulate the quantity of seed to be dropped.

O is a slide, movable longitudinally in suitable bearings under the bottom L, and having a slot, P, of V shape, corresponding with that 65 in the bottom L, so as to form the seed-opening. The said slide is forced automatically in a forward direction by the action of a suitably-arranged spring, Q, so as to keep the seed-opening normally closed.

R R designate the handles, which are pivoted to the sides of the frame and connected in the usual manner by a round, S. Pivoted upon the ends of the latter are a pair of arms, S' S', which extend downwardly and are provided with slots T, working over pins or studs U upon the sides of the rear end of the frame. The lower ends of the said arms form bearings for the ends of the axle of a concave covering or pressure-roller, V, which serves to pack the 80 soil around the seed. The arms, it will be seen, may be readily adjusted, so as to place the roller at the desired elevation.

W designates the seeding wheel or disk, which is mounted upon the axle of the machine within the hopper by means of a collar, X, having a set-screw, Y. The said seed-wheel consists of a disk having in its periphery a series of radial openings, Z Z, adapted to receive the fingers or stirrers A' A', which are held adjustably in the said openings by means of clamping-plates B', secured by means of set-screws C'. These fingers are adapted to engage a lug, D', projecting upwardly from the slide O through the slot M of bottom L, which 95 said slide is thereby operated as the machine progresses over the ground. By increasing or diminishing the number of fingers A' any desired distance may be left between the seed deposits.

From the foregoing description, taken in connection with the drawings hereto annexed, the operation and advantages of this invention will be readily understood. It is simple in

construction, easily manipulated, and effective in operation, and it may be used with equal efficiency for planting seeds of various kinds, such as corn, peas, peanuts, cotton, and the like.

5 Having thus described our invention, we claim and desire to secure by Letters Patent of the United States—

1. In a seed-planter, the combination, with the frame, of the plow and coverer-standard secured to the front end of the same, and constructed of a single piece of metal, the rear leg of which is slit and bent so as to form the attaching - flanges, and the covering - blades connected pivotally to the rear leg of the said

15 standard, substantially as and for the purpose set forth.

2. In a seed-planter, the combination, with the planter-frame, of the handles pivoted to the sides of the same, and having pivoted slotted 20 arms working over studs upon the sides of the

said frame, and the concave compressing-roller journaled between the lower ends of the said arms, substantially as and for the purpose set forth.

3. In a seed-planter, the herein-described 25 seeding-wheel, consisting of a disk the periphery of which is provided with radial openings, in combination with the fingers adjustable in the said openings, and the clamping - plates adapted to retain the said fingers in position, 30 substantially as and for the purpose set forth.

In testimony that we claim the foregoing as our own we have hereunto affixed our signatures in presence of two witnesses.

ANDREW SAVAGE.
JOHN Y. SAVAGE.
